UNITED STATES PATENT OFFICE.

JESSE C. WELCH, OF TACOMA, WASHINGTON, ASSIGNOR TO THE J. C. WELCH MFG. CO., OF TACOMA, WASHINGTON, A CORPORATION OF WASHINGTON.

SERVING-WAGON.

1,323,511.

Specification of Letters Patent.

Patented Dec. 2, 1919.

Application filed January 22, 1919. Serial No. 272,440.

To all whom it may concern:

Be it known that I, JESSE C. WELCH, a citizen of the United States, and resident of the city of Tacoma, county of Pierce, and 5 State of Washington, have invented certain new and useful Improvements in Serving-Wagons, of which the following is a specification.

This invention relates to improvements in 10 serving wagons, and has for its principal object to provide for an improved and novel construction in a device of this character, to provide a hubless vehicle wheel, which is mounted upon rollers, to provide a serving car in which the space intermediate the 15 wheels is inclosed and contains receptacles which are slidable in a direction parallel with the axis of the wheels. Other objects will be disclosed as my device is more fully 20 explained in the following specification, illustrated in the accompanying drawings and pointed out in the appended claims.

Figure 1 is a side elevation of my device with parts broken away.

25 Fig. 2 is a sectional plan view of Fig. 1.

Fig. 3 is a part sectional elevation of same.

Fig. 4 is an enlarged fragmentary section of my improved wheel.

30 Fig. 5 is an enlarged elevation of one roller upon which the wheel revolves.

Fig. 6 is a side view of a serving wagon having a modified form of interior frame.

Referring more particularly to the drawings numeral 1 indicates side frames of the 35 serving car. The frames are spaced in parallel relationship and are joined together by end frames 2, thus forming a rectangular body. The body thus formed is mounted upon a hollow inner frame 3, 40 which passes transversely through the said body, the said frame preferably being rectangular in cross section, but I do not wish to limit it to this particular shape, as in 45 some instances, as is illustrated in Fig. 6, it is desirable to make the frame circular.

Inner frame 3 is shown with its sides inclined obliquely, and extends beyond the side frames at either end. This position 50 may be changed as desired. A series of roller carriers 4, are mounted upon the inner frame 3 beyond the side faces of the frame 1 and revolvably support a roller 5. By means of a threaded mounting 5', the 55 rollers may be adjusted inwardly or out-

wardly to facilitate removing or placing the wheels in position.

It will be understood that the rollers 5 are arranged in two groups these being shown as containing four each, and that the 60 rollers in each group lie in a plane which is parallel with the side frames 1. The inner frame 3 is stationary with respect to the body and being hollow, is utilized for holding slidable cabinets 6 within which are 65 mounted shelves 7 for supporting dishes and the like.

The cabinets 6 are slidable within the inner frame 3, and may be partially withdrawn or completely removed as desired. 70 The outer ends of cabinets 6 are closed by means of doors 8.

The ends of the body are supported upon pivoted dolly wheels or casters 9, which stabilize it when necessary, but the main 75 weight of the body rests upon the hubless wheels as will be more fully described later.

Hubless wheels are mounted one upon each group of rollers 5, and each consists of the circular rim 10, upon the outer periphery of which a tire 11 is mounted, and upon the inner periphery of which a circular rail 12 is fastened. The web of the rail 12 fits into grooves 13 of the rollers 5, thus forming a tractive surface for the said rollers. It will be understood that the tire 11 80 bears against the floor, and as the body is pushed forward, the wheels revolve about the inner frame 3.

My peculiar arrangement and construction of the wheels and their mountings upon the revoluble rollers constitute a noiseless and nearly frictionless form of vehicle wheel, which while here shown on a serving wagon, yet is applicable to many other uses. 95 In itself, apart from the serving wagon, the wheel constitutes the most important feature of my device.

The construction of my wheel and the inner frame permit of the elimination of an 100 axle for the said wheels, and also permit of the better utilization of the space usually occupied by the axle than could be made otherwise.

The outer face of each wheel 10 is 105 enclosed by the periphery of an end piece 15 which is fixed to and extends beyond the edge of the frame 3, the members 15 being provided with the doors 8 previously mentioned to permit access to the shelves 7. 110

The space at either end of the wagon and intermediate the side frame is utilized for shelves 16, etc., for the purpose of storing and carrying any desired articles.

5 In Fig. 6 I have illustrated a circular inner frame 3 which I prefer to use in some instances and which is mounted similarly to the rectangular frame 3 and serves in the same capacity.

10 Many minor changes may be made in the construction of my device as herein illustrated and described, without departing from the scope of my invention, and I do not wish to be limited except in accordance 15 with the appended claims.

15 What I claim as my invention is:

1. A vehicle comprising a body, an inner frame extending beyond the sides of the said body, rollers mounted upon the extending 20 end of the said inner frame, hubless wheel means mounted upon the said rollers; said wheel means comprising a circular rim, a tire mounted upon the outer periphery of the said rim, and a circular rail secured to 25 the inner periphery of the said wheel, whereby the wheel is revolvably held in contact with the said rollers.

2. In the device of the class described, the combination of a pair of parallel side frames, 30 a pair of end frames connecting the said side frames, a rectangular inner frame ar-

ranged transversely of and extending beyond said side frames, cabinets slidably mounted within the said inner frame, rollers arranged in a parallel group and secured 35 to the end of the said inner frame, wheel means revolvably mounted upon said group of rollers; said means embodying a circular rim, a tire mounted upon the outer periphery of the said rim, a circular rail mounted 40 upon the inner periphery of the said rim and in contact with the said rollers, whereby the wheel may revolve upon the rollers.

3. A service car comprising a body, two wheels consisting of rings having inner and 45 outer treads, bearing members carried by the body and engaging the inner tread, said body having containers adapted to be gotten at through the opening in said wheels.

4. A service car comprising a casing, two 50 wheels consisting of rings having inner and outer treads, bearing devices carried by the casing and engaging the inner treads, the casing having compartments accessible through the central openings of the wheels 55 and other compartments accessible from the sides of the casing outside of the area of said wheels.

Signed at Tacoma, Washington, this 16th day of January, 1919.

JESSE C. WELCH.
